(57) **CLAIM**

The ornamental design for a condenser shroud for DC cooler, as shown and described.

DESCRIPTION

This invention was made with Government support under contract DE-FC26-04NT42106, awarded by the United State Department of Energy. The Government may have certain rights in this invention.

FIG. 1 is a front view of the condenser shroud for DC cooler;
FIG. 2 is a rear view thereof;
FIG. 3 is a top view thereof;
FIG. 4 is a bottom view thereof;
FIG. 5 is a right side view thereof;
FIG. 6 is a left side view thereof;
FIG. 7 is a front perspective view thereof; and,
FIG. 8 is a rear perspective view thereof.
